UNITED STATES PATENT OFFICE.

FERDINAND G. STALLMAN, OF PITTSBURGH, PENNSYLVANIA.

TYPEWRITING MACHINE.

Application filed November 8, 1924. Serial No. 748,742.

My invention relates particularly to improvements upon the typewriting machine disclosed in my former Patent 966,714, granted August 9, 1910, in which is employed a 5 rotary or pivoted typewheel or segment provided with type, and a depressible keyboard or similar movable member for actuating and controlling the type-wheel or segment to bring the proper characters into position 10 for imprinting on the paper.

The principal objects of my invention are:

First. To provide an exceedingly simple, compact, light and comparatively inexpensive machine of this character, which will 15 have the functions and utilities of a first-class typewriter and be exceedingly efficient, though especially adapted to the requirements of literary people, students, and small store keepers.

Second. To provide improved and simplified mechanism for actuating and controlling the typewheel or segment by the keyboard, such that resisting force may be exerted at the proper periods and that the 20 tension of the several strokes will be equal.

Third. To provide improved means for shifting the type-wheel or segment in an axial direction when necessary for shifting from one line of type to another, and to lock 25 the typewheel in proper position for printing.

Fourth. To provide a single rotatable type carrier having the type at one end and shiftable axially to select the proper characters and to actuate the same through the keyboard.

Fifth. To provide simple and efficient ribbon mechanism, paper feed, escapement mechanism, and the other instrumentalities 35 necessary for a complete typewriting machine.

Sixth. To provide means for procuring elasticity in the working parts.

Other objects will be apparent from the 45 following detailed description and the appended claims.

In the drawings, Figure 1 is a top plan view of a typewriting machine constructed according to my invention with the keyboard depressed to its lowest position;

Figure 2 is an elevation of the right hand side of the machine with the type wheel in printing position;

Figure 3 is a side elevation of the left 55 hand side of the machine with parts in section;

Figure 4 is a bottom plan view of the machine;

Figure 5 is a detail view of the shield;

Figure 6 is a bottom plan view of the 60 typewheel actuating mechanism with the type wheel in section;

Figure 7 is an end view showing the construction of the typewheel and the platen;

Figure 8 is a detail of the slide bar which 65 controls the selection of the type;

Figure 9 is a plan view of a portion of the base showing the shift keys and the space key;

Figure 10 is a transverse section through 70 the keyboard with parts in elevation showing the cushion means for the mechanism;

Figure 11 is a cross section through the keyboard;

Figure 12 is a section through the key- 75 board with parts omitted;

Figure 13 is a top plan view with parts in section of the paper carriage;

Figure 14 is an end view of the same;

Figure 15 is a detail view of the clutch 80 with a yielding spring action together with the controlling means for bringing the type into printing position;

Figure 16 is a plan view of the ribbon 85 feeding mechanism.

The machine comprises a base 1 which is of suitable size and shape and supports the paper carriage, escapement mechanism, shift keys and space key. Pivoted thereto at its lower end is an upright frame 2 comprising a cross bar and two side uprights. Pivoted to these uprights at their upper ends at 2' is a rearwardly extending frame member 3 which carries the type mechanism keyboard and various other instrumentalities as will be hereinafter apparent. Carried by this frame member is a sliding plate 4 (see Figure 8), which has extensions 5 from each side, which extensions are provided with steps 6. These various steps 100 engage the key stems when depressed to stop the rotation of the type wheel shaft at the proper point for the selection of the desired character.

Supported in bearing brackets 7' from the under side of the top member 3 is a typewheel shaft 7 provided with a pinion 8 which meshes with a rack 9 on the under surface of the plate 4. Mounted on the shaft 7 is a sleeve 10 having a gear 11 at 105 one end, lugs 12 and a cam flange 16. This sleeve is loosely mounted on the shaft, but

when the wheel 11 is turned as hereinafter explained, the shaft is normally turned by means of a resilient extension 13 connected to the pinion 8 or its hub and carrying a roller 15 at its free end adapted to engage a depression in the flange 16. A spring 14 surrounds the sleeve 10 and is connected to the lugs 12. It is obvious that when the wheel 11 is turned the engagement of one or 10 the other of the lugs 12 with the flexible member 13 will turn the pinion 8 until the sliding movement of the plate 4 is stopped by the engagement of one of the steps 6 with the depressed key stem. Then, al- 15 though the member 3 continues its downward movement and the rotation of the wheel 11 is continued, the roller 15 will move out of the depression in the flange 16 and the various spring connections will permit 20 the continued revolution of the wheel 11 although the pinion 8 and typewheel shaft 7 are held against rotation. When pressure is released the resilient members return the parts to normal position. The action is the 25 same, no matter in which direction the wheel 11 is rotated.

Movement is given to the wheel or gear 11 in the following manner:

Supported in the sides of the top frame 3 is a shaft 17 which has at one end outside the frame a pinion 18 which meshes with a drive rack 19 that is curved as shown. This rack 19 is carried by an arm 19' which is pivoted to turn about the axis of the connection of the parts 2 and 3 and has a downward extension 20 adapted to contact with the top side of the base 1 in order that the rack may move forward and rearward when the top plate and other parts are operated by the shift keys as hereinafter set forth. On the shaft 17 is a sleeve 21 which can slide longitudinally of the shaft but is mounted to rotate therewith. This sleeve has two gears 22 and 23, either of which 45 can be brought into gear with the wheel 11. Supported in a bearing in the under face of the top plate 3 is an arm 24 having one end downturned at 25 to be engaged by the keys on the keyboard as hereinafter set forth, and at the other end is provided with a finger 26 engaging with a groove 27 in the sleeve 21. Rocking of the arm 24 will move the sleeve in one direction or the other and bring either gear into engagement with the 50 gear 11. As the shaft 17 is always rotated in the same direction in the down stroke of the keyboard or top member 3, the typewheel will be rotated in different directions depending upon which gear 22 or 23 is in engagement with the wheel 11. Any desired spring arrangement may also be provided to return the arm 24 to normal position.

There are two shift keys 28 and 29 at the 65 side of the machine. The arrangement of

these is well shown in Figures 3, 4, 9, 10 and 11. The shift key 28 is used for writing capitals and it shifts the typewheel through an offset 30 which engages the bell crank 31 of the rod 32 and shifts the typewheel 33 70 endwise. The shift key 29 is attached to an arm 34 extending from the frame 2 toward the front, and pressure on this shift key rocks the frame 2 moving the top member 3 and all parts carried thereby toward the 75 rear and thereby positioning a different row of type.

Mounted on shaft 7 is a typewheel 33 having three rows of type and sides or flanges 34' and 35. Each flange is provided with a long slot 36 that registers with the slot 37 in the bushing 38 in order to attach and detach the typewheel. A sliding shift rod 32 is mounted in a bearing 39 in the under face of the type member 3, and a collar 40 is positioned near the bearing to limit the amount of shift by the shift key 28 for writing capitals.

The keyboard proper is carried by the top member 3, which may be termed a keyboard lever, since it acts as a lever and also carries the keyboard, and said keyboard consists of two plates 41 and 42, the bottom plate preferably being adjustable and provided with slots for the passage of the 95 keys. Keys 43 are held in position by flat springs 44 located between the plates 41 and 42. The plates can be detached by removing the plate 41 from the frame 3. A spring 45 connects the two plates and permits the plate 42 to yield when the slide bar 4 comes against an actuated key stem. Whenever a key is depressed it passes down into position to engage one of the shoulders 6 on the extensions 5 of the slide 4. 100 A depression of the keyboard lever or top frame rotates the shaft 7 until a shoulder on the slide bar comes against the depressed key stem, which then holds the slide bar against further movement. The continued rotation of the shaft 17 and wheel 11 is permitted as before set forth, and the centering and printing operations follow. It will be noticed that the depression of a key in the row below the desired key will not affect the operation, since the plate will be stopped by engagement with the stem of any row before it can engage the stem of any key in a lower row.

The keyboard lever 3 is returned to upper position when pressure thereon is released by means of a spring 46 attached to a spiral cam 47 on the rockshaft 17. A spiral counterbalance spring 48 may also be provided for the keyboard lever.

Whenever a key is depressed it at first pushes the arm-plate or angle bar levers 49, one of which is formed with a depending arm 50 on one end, one with a horizontal connecting arm 51, and one with an L- 130

shaped arm 52 and connected to an arm 50 by a bar 53, which through the medium of an arm 24 having an end 25 and a finger 26, make the connections for shifting the gear sleeve 21 by a series of keys on the left side of the keyboard.

A thin cup-shaped flange 54 is fastened to one end of the sleeve to reduce the amount of shift when it passes over the lug 55 through the slot 56. A spring 57 returns the gear sleeve to its normal position, and as the flange rotates it is held from shifting by the lug 55 until the slot 56 comes in line with said lug.

Therefore when any key on the left side of the keyboard is depressed it will engage the gear on the right side and cause the typewheel to rotate in one direction and the slide 4 to approach the keys of the left side, and when the key has completed the up-stroke, the spring 57 will throw the other gear into engagement ready for the depression of any key on the right side of the key board to rotate the typewheel in the opposite direction.

The springs for supporting the keys are in the form of thin plates divided by long slots forming flexible fingers that can be depressed individually and rest on the shoulders of the keys. The edges of angle bar 49 rest against the springs under the shoulder of the key. The angle bar levers are pivoted to rock on the shaft 59 which is either supported in snap bearings 60 or held in place by a spring 61 (see Figure 12).

The carriage comprises an open ended sheet metal member having open bearings 62 in which is mounted a feed roll 63. An upper guard part 64, which acts as a shield, overlies bearings for a second feed roll 65 and has guides 66 and lugs 67 in which is hinged the shield piece 68. The paper *a* is rolled up in the carriage, passes between the feed rolls 63 and 65 under the guard plate and the shield 68, and over the anvil or platen 69. As shown in Figure 7, this platen is covered with a rubber band 70 and over that a thin tape 71 of hard tough material passes and is coiled in a receptacle 72. Over the whole is placed a detachable cover plate 73.

The carriage may be moved in any desired manner, as by means of a spring drum 74 connected or geared to the carriage and having rigid therewith an escapement wheel 75, which is alternately engaged by resilient pawls 76 and 78 in the usual manner to allow the wheel a step by step movement. The pawls are carried by a lever 79 pivoted at 80 and also having a guard piece 81 overlying the pawls as shown in Figure 9. The outer end 79' of the lever 79 acts as a space key and is manually operated for spacing between words. A spring 82 fastened to the lever 79 has an upward extension 83 adapted

to be engaged by a projecting arm 84 of the top plate 3 to automatically operate the escapement when any type is printed. A spring 82' returns the escapement lever after operation.

One of the feed rolls of the carriage has a telescopic rod 85 with a finger piece 86 by which to turn the same for line spacing. The rod has a circular groove 87 engaging the bearing and a pin 88 sliding in a key-way 89 and a loose ring 90. At the opposite end a notched disc 91 engages a pin 92 to hold the parts against accidental rotation. The carriage is guided for the alinement of the writing by an angle bar 93 sliding in a groove 94 in the base 1, and held in place by a plate 95. The bar 93 has a lug 96 which limits the travel of the carriage by coming into engagement with a stop on the base.

Studs 97 are adapted to carry ribbon spools which will have roughened edges 98 for engagement by a toothed pawl 99 for holding purposes held by a spring 99' and a feeding pawl 100 for each spool. The bar 101 holds the ribbon spools in place. A flexible member 102 fits into a pocket of an oscillating lever 103 fulcrumed at 104 and has a roller 105 in the path of a cam 106. When the keyboard is depressed, the cam feeds the ribbon through the medium of the flexible member 102, moving it the distance of one tooth, the periphery of the spools having very fine teeth which feed the ribbon slowly and necessitate re-winding only at long intervals. Any desired mechanism other than that shown can be used for feeding the ribbon. The ribbon passes from one spool around guide 107 through the ribbon guide 107' and round another guide 107 to the other spool. This mechanism is illustrated in detail in Figure 16.

Lugs 108 are employed to stop the movement of the slide bar 4. A latch member 109 has a hook 110 on its lower end adapted to engage with a side of the base 1 and is carried by a spring 111 fastened to the rack member 19, and this acts to lock the upper member 3 to the base and to cushion the upward movement of the member 3. A latch 112 is also employed to lock the parts against disengagement. Lugs 113 and 114, respectively, hold the rack 20 and keyboard lever against lateral movement.

This application is a substitute for my prior application Serial No. 637,876, filed May 9, 1923, and allowed February 15, 1924, with some slight changes and the addition of some minor features not illustrated and described in said prior application.

It will be evident that various modifications may be made in the embodiment of my invention illustrated in this application without departing in any way from the

spirit of the invention. Certain features may be used without others, or in different relations. I desire it to be understood that the invention is to be regarded as limited only by the scope of the appended claims.

Having thus described my invention, what I claim as new and desire to secure by Letters Patent of the United States is:

1. In a typewriting machine, a bed plate, a pivoted frame rising from one end thereof, and a top plate pivoted to said frame and carrying the type mechanism, operating devices therefor, keyboard and ribbon mechanism.
2. In a typewriting machine, a bed plate, a pivoted frame rising from one end thereof, a top plate pivoted to said frame and carrying the type mechanism, operating devices therefor, keyboard and ribbon mechanism, an escapement mechanism on the bed plate, and means for operating the escapement mechanism by the rocking of the top plate.
3. In a typewriting machine, a bed plate, a platen thereon, a movable carriage adjacent the platen, a top plate supported from the bed plate for movement about two pivots and carrying the type and ribbon mechanism, and means for selecting a given type and impressing it on paper passing over the platen, said means operated by rocking the top plate.
4. In a typewriting machine, a bed plate, a platen thereon, a top plate pivotally supported from the bed plate to move in two directions relatively thereto, a shift key for moving the top plate in one direction, a keyboard on said top plate, means controlled by the keyboard and operated by the movement of the top plate in the other direction, type on said top plate, and connections whereby the two movements of the top plate select the desired type.
5. In a typewriting machine, a bed plate, a top plate supported thereby, a key wheel carried by the top plate, means for giving the key wheel variable degrees of rotation, means for moving the key wheel axially independently of the top plate, and means for moving the key wheel and top plate together in the direction of the axis of the key wheel.
6. In a typewriting machine, a bed plate, a top plate pivotally supported thereby, a key wheel carried by the top plate, means whereby the pivotal movement of the top plate gives the wheel variable degrees of rotation, a shift key for moving the key wheel longitudinally with the top plate, and means for moving the key wheel longitudinally independently of the top plate.
7. In a typewriting machine, a bed plate, a standard pivoted thereto, a top plate pivoted to said standard, a type wheel shaft rotatably mounted in said top plate, a keyboard on said top plate, a sliding plate

geared to the type wheel shaft, and means for stopping the movement of the sliding plate at different positions according to the key depressed.

8. In a typewriting machine, a bed plate, a standard pivoted thereto, a top plate pivoted to said standard, a type wheel shaft rotatably mounted in said top plate, a key board on said top plate, a sliding plate geared to the type wheel shaft, means for stopping the movement of the sliding plate at different positions according to the key depressed, and means whereby the top plate may continue its pivotal movement independently of the point at which the rotation of the type wheel shaft is stopped.

9. In a typewriting machine, a type wheel, a gear for rotating said wheel, a plurality of gears adapted to be shifted to engage the first named gear to rotate it in opposite directions, and means for preventing said shifting movement except when the type wheel is in normal position.

10. In a typewriting machine, a type wheel, a shaft on which it is mounted for longitudinal movement, means for rotating the type wheel in either direction, means for moving it longitudinally with the shaft, and means for moving it longitudinally on the shaft.

11. In a typewriting machine, a base plate, a top plate pivotally carried thereby, a key wheel on said top plate, ribbon mechanism also carried by the top plate, escapement mechanism on said base plate, means whereby the pivotal movement of the top plate operates the escapement, feeds the ribbon, and rotates the type wheel, and means for moving the typewheel longitudinally of its axis either with the top plate or independently thereof.

12. In a typewriting machine, a base plate, a top plate pivotally supported thereby, a key wheel on said top plate, a shift key for moving the wheel longitudinally with the top plate, and a shift key for moving the wheel independently of the top plate and groups of shift keys on the keyboard for reversing the rotation of the type wheel.

13. In a typewriting machine, a type carrier and a movable key board for variably positioning the said type carrier, said key board consisting of plates and spring connections between said plates which act as buffer means for checking the rotation of the type carrier.

14. The combination, in a typewriting machine, of an open spring-barrel or paper-holder, and rollers contained in open bearings adapted to spread the opening of said barrel; the end of one roller having a notched flange adapted to alternately engage a lug on one of the bearings by pressure of the barrel when the roller is turned for line spacing.

15. In a typewriting machine, a type carrier, a movable keyboard member, elastic or buffer means for variably positioning the type carrier, driving mechanism, and means 5 for locking and unlocking the type carrier to and from the driving mechanism so as to hold the buffer means against reaction until after the imprint is made.
16. In a typewriting machine, a type carrier, a platen or anvil, a magazine containing a supply of tape of smooth hard texture which overlies said platen, and means for holding the tape in operative position.
17. In a typewriting machine, a type carrier, a platen or anvil, a rubber band covering the surface of the platen, a hard smooth tape overlying the rubber band, and means for holding the band and tape in position.
18. In a typewriting machine having a de- 20 pressible keyboard lever, escapement mechanism comprising an escapement rack, and an escapement lever having pawls to co-operate with said rack, a handle at one side and an extension at the other side, said 25 handle being operated to space without printing, and said extension being operated by the depressible keyboard lever to space with printing.
19. In a typewriting machine, a de- 30 pressible key board, independently depressible keys therein, a type wheel, means whereby depression of certain keys causes the depression of the key board to rotate the type wheel in one direction and means actuated by other 35 type keys to control said means so that the subsequent depression of the key board will rotate the type wheel in the other direction.
20. In a typewriting machine, a key board 40 lever, a base, or bed-plate, snap-latching means to attach said keyboard lever to the base, an eccentric handle or pivotal key lever for locking and unlocking the snap-latch.
21. In a typewriting machine, a keyboard 45 lever, a base or bed-plate, snap-latching means to attach said keyboard lever to the base, and means for locking and unlocking the snap-latch.
22. In a typewriting machine, a keyboard 50 lever, a base or bed-plate, and means for locking the keyboard to the base, and unlocking it from the base.
23. In a typewriting machine, a keyboard lever or frame supporting a typewheel at its free end, a stop bar or slide for contact action in either direction adapted to approach different degrees of distance from a central position along either side of the keyboard to position the type, and by the depression of the entire keyboard to make an impression of the type upon paper or 60 the like.
24. In a typewriting machine, a de- 65 pressible key board, a type wheel carrying shaft mounted to swing with said key board, de- pressible keys in said key board, means whereby the depression of the key board by different groups of keys rotates the shaft in different directions, means for moving the type wheel relatively to the key board, and means for moving the type wheel in the 70 same direction with the key board.
25. The combination in a typewriting ma- 75 chine, of a base for same, a reducible carriage having rollers held together by a spring-barrel, an angle bar or rail as part of the barrel adapted to support one of the rollers containing a slide rod with a circular groove adapted when extended to snap in the bearing to lock it, and the base containing a groove for the rail to guide the 80 said carriage.
26. In a typewriting machine, a typewheel 85 or segment, a type carrier having one end in the form of a hook to drive a typewheel with a through opening for the entrance of the hook, and having a circular grooved hub for shift connection, and the typewheel thereby adapted for ready attachment and detachment.
27. In a typewriting machine, operative 90 type mechanism, ribbon spools having knurled flanges, a flexible feed lever, a holding pawl, means by bending the said lever to feed the said spools a fine degree of motion for each successive type to be printed. 95
28. In a typewriting machine, operative 100 type mechanism, ribbon spools having knurled flanges, a holding pawl, a feed lever having a roller and being cam operative against the said roller and the said lever adapted to engage the flanges to feed the ribbon fine degrees of motion for each successive type to be printed.

In testimony whereof I affix my signature.

FERDINAND G. STALLMAN.
